UNITED STATES PATENT OFFICE

2,505,336

GUN TYPE OIL BURNER

Thomas W. Murphy, Narberth, Pa., assignor to
Monarch Manufacturing Works, Inc., Philadelphia, Pa., a corporation of Delaware

Application February 28, 1946, Serial No. 650,859

4 Claims. (Cl. 158—76)

1

This invention relates to an oil burner and has particular reference to improved means insuring proper relationship of the combustion air to the oil stream or spray to insure uniform and proper combustion.

Difficulties have heretofore been experienced in securing the proper uniform flame in oil burners by reason of the fact that there is interference with the stream of air by the ignition electrodes and the oil line. As a result of unequal distribution of the air, there may exist substantial asymmetry of the flame, i. e., it may start on one side, as viewed from above, several inches closer to the cone ring than on the other side, with a resulting uneven distribution of heat in the furnace.

In accordance with the present invention, air guiding means are provided for the purpose of insuring uniformity of the air stream and proper directing thereof relative to the oil spray.

The foregoing general object of the invention, as well as other objects particularly relating to details, will become apparent from the following description read in conjunction with the accompanying drawing, in which:

Figure 1 is a vertical section through an oil burner embodying the invention;

Figure 2 is a vertical section taken on the plane indicated at 2—2 in Figure 1; and

Figure 3 is a vertical section taken on the plane indicated at 3—3 in Figure 1.

A blow tube 2 of conventional character receives air from the usual blower or fan 4 provided with blades 6. Within the blow tube, there is a conventional stabilizer 8 consisting of angular blades to impart rotation to the air as it passes through the blow tube. Extending centrally through the blow tube is the oil line 10 terminating in the usual spray nozzle 12, from which emerges the oil in the form of a divergent spray. Porcelain insulating tubes 14 are mounted in the stabilizer and carrying the ignition wires 16. The foregoing is quite conventional.

At the end of the blow tube, there is a cone or choke ring 18. Heretofore, it has been customary to provide this choke ring, if vanes are provided at all, with angular vanes sometimes spiralling in a direction to aid the spin imparted to the air by the stabilizer, and, at other times, spiralling in the opposite direction so as to reverse the direction of spin. In accordance with the present invention, however, there are provided a plurality of blades 20, each being considerably longer than the width of the space between blades of the form indicated in Figures 1 and 2 extending axially of the blow tube and terminating in merg-

2

ing fashion as indicated short of the outlet edge of the cone ring.

By reason of this construction, there is secured a proper presentation of a cylindrical stream of combustion air to the oil spray. Due to the stabilizer 8, or other spinning means not shown, the air is given a spin and expands outwardly toward the periphery of the blow tube. The outermost portion, or an annulus of this air stream is then straightened out by the blades 20 into a multiplicity of axially flowing streams which are then directed inwardly toward the spinning core by reason of the converging curvature of the cone ring. While the high peripheral velocity of this outer region of air is thus interrupted, the central core of air retains its spin with the result that a suitable breaking up or distribution of flow occurs causing the air emerging from the cone ring to flow in uniform fashion with respect to the axis of the spray despite the usually interfering presence of the electrodes and the oil line. The result is uniformity of the region of beginning of ignition of the oil and a resulting uniform and symmetrical flame.

It may be pointed out that uniformity is also achieved if the stabilizer is absent, and spin is secured in some other fashion, for example, by tangential introduction of air into the blow tube.

While the blades are conveniently and desirably carried by the cone ring, it is found that they may be located anywhere between the cone ring and the stabilizer (if the latter is present) so as to have the function of providing parallel axial flow at the outer walls of the air passage.

The construction of the cone ring as illustrated and described offers a further advantage in ease of manufacture, since the mold may be made with the use of match plates, thus eliminating the use of a core.

It will be clear that the principles of the invention may be embodied in various forms without departing from the scope of the invention as defined in the following claims.

What I claim and desire to protect by Letters Patent is:

1. In combination, a nozzle for providing an oil spray, and means for directing a cylindrical stream of air having a spinning core within an outer portion flowing axially therewith and to the spray of oil to support combustion thereof, said means including a blow tube, means within the blow tube for imparting to the air flowing therethrough rotation about the axis of the blow tube, a convergent cone ring terminating the blow tube in advance of the region of the oil

spray, and a multiplicity of radially disposed blades projecting inwardly from said cone ring and extending parallel with the longitudinal axis of the cone ring, each of said blades being considerably longer than the width of the space between blades projecting inwardly from the walls of the cone ring, said blades forming air flow passages for directing the flow of air passing through said passages into the core along and toward the axis thereof within the cone and beyond the nozzle.

2. In combination, a nozzle for providing an oil spray, and means for directing a cylindrical stream of air having a spinning core within an outer portion flowing axially therewith and to the spray of oil to support combustion thereof, said means including a blow tube, means within the blow tube for imparting to the air flow therethrough rotation about the axis of the blow tube, a convergent cone ring terminating the blow tube in advance of the region of the oil spray, and a multiplicity of radially disposed blades projecting inwardly from said cone ring and extending parallel to the longitudinal axis of the cone ring, each of said blades being considerably longer than the width of the space between blades projecting inwardly from the walls of the cone ring and parallel to the axis thereof from a point back of the nozzle to a point between the nozzle and the edge of the cone ring to define axial passages for directing the flow of the outermost portion of the air flowing through said passages into the rotating core of the air stream along and toward the axis thereof between the nozzle and the edge of the cone ring.

3. An oil burner comprising a blow tube, said blow tube having a converging discharge end, a nozzle mounted substantially centrally within said blow tube directing an oil spray toward said discharge end, means for directing a whirling stream of air through said blow tube past said nozzle, and means for directing a plurality of

axially flowing streams of air against the converging discharge end of the blow tube, said axially flowing streams of air being directed inwardly by the converging end of the blow tube 5 into the central whirling stream of air and oil reducing the divergence and producing a symmetrical whirling flow of the air and oil discharging from the blow tube.

4. An oil burner comprising a blow tube, said 10 blow tube having a converging discharge end, a nozzle mounted substantially centrally within said blow tube directing an oil spray toward said discharge end, means for directing a whirling stream of air through said blow tube past said nozzle, and means for directing a plurality of axially flowing streams of air against the converging discharge end of the blow tube, said axially flowing streams of air being directed inwardly by the converging end of the blow tube into the periphery of the central whirling stream of air 15 and oil within the discharge end of the blow tube reducing the divergence and producing a symmetrical whirling flow of the air and oil discharging from the blow tube.
